187,447

COMBINED ASH TRAY AND CIGARETTE CONTAINER OR SIMILAR ARTICLE

Carroll N. Jolly, Portland, Oreg.

Application November 4, 1957, Serial No. 48,333

Term of patent 14 years

(Cl. D85—2)

Fig. 1

Fig. 2

Fig. 3

Fig. 4

Fig. 1 is a plan view of a combined ash tray and cigarette container or similar article showing my new design;

Fig. 2 is a side elevational view;

Fig. 3 is a view looking into the top counterpart of Fig. 4; and

Fig. 4 is an enlarged partially exploded view showing the lower half of the article.

The broken line showing of a portion of a cigarette in Fig. 4 is for illustrative purposes only.

I claim:

The ornamental design for a combined ash tray and cigarette container or similar article, as shown and described.
